FIG. 1

FIG. 2

FIG. 3

FIG. 4

FIG. 5

FIG. 6

FIG. 7

FIG. 8

FIG. 9

FIG. 1 is a rear elevational view of a display case showing my new design;

FIG. 2 is a front elevational view;

FIG. 3 is a left side elevational view;

FIG. 4 is a right side elevational view;

FIG. 5 is a top plan view;

FIG. 6 is a bottom plan view;

FIG. 7 is a rear elevational view of a second embodiment of a display case showing my new design wherein the height is greater;

FIG. 8 is a front elevational view thereof; and

FIG. 9 is a rear and top perspective view of the display case shown in FIGS. 1-6.

The top and bottom plan views of the second embodiment are identical to those shown in FIGS. 5 and 6, and the side elevational views thereof are substantially similar to FIGS. 3 and 4 except for different proportions.

I claim:

The ornamental design for a display case, substantially as shown and described.
